UNITED STATES PATENT OFFICE

2,074,525

WATCH

Richard H. Whitehead, New Haven, Conn., assignor to The New Haven Clock Company, New Haven, Conn., a corporation of Connecticut

Application November 24, 1936, Serial No. 112,482

3 Claims. (Cl. 58—88)

This invention relates to improvements in watches.

One object of this invention is to provide an improved watch structure in which the dial-plate or the like is secured to and carries the movement-unit of the watch, the movement-unit being insertable into the center-band of the watch from the front, with the dial-plate engaging against the center-band and being clamped there-10 against by the bezel-ring.

Another object of this invention is to provide an improved watch structure formed of simple elements readily manufactured and readily assembled to produce an efficient construction at 15 minimum cost.

With the above and other objects in view, as will appear to those skilled in the art from the present disclosure, this invention includes all features in the said disclosure which are novel over 20 the prior art.

In the accompanying drawing, in which one way of carrying out the invention is shown for illustrative purposes:

Fig. 1 is a front elevation illustrating a watch 25 made in accordance with one embodiment of the invention;

Fig. 2 is an enlarged view similar to Fig. 1, but with the bezel-ring removed;

Fig. 3 is a sectional view on line 3—3 of Fig. 2, 30 with the bezel-ring in position and with some of the parts in elevation; and

Fig. 4 is a perspective view of the dial-plate.

In the description and claims, the various parts 35 are identified by specific names for convenience, but they are intended to be as generic in their application as the prior art will permit.

Referring to the drawing, the watch 10 has a usual center-band 11 with a usual back-plate 12 secured thereto in any suitable or usual manner. A movement-unit 13 has a front movement-plate 14 and a rear movement-plate 15, secured 40 together by means of pillars 16, the movement-unit including the usual gearing and other mechanism (not shown) forming part of a watch.

The dial-plate or the like 17 preferably is formed of sheet-metal having an annular shoulder 18 and supporting-feet 19 adapted to engage against the annular edge 20 of the center-band 11. The dial-plate 17 also has integral fingers 21 adapted to extend in the notches 22 of the front movement-plate 14 and be bent about the latter to secure the dial-plate 17 and movement-plate 14 together. The entire unit consisting of the movement-unit 13 and the dial-plate 17 is 55 assembled with the center-band 11 by inserting the movement-unit 13 through the front of the center-band 11 and engaging the supporting-feet 19 against the annular edge 20 of the center-

band, whereupon the bezel-ring 23 is snapped or clamped in position in the usual manner to the center-band 11, which clamping brings the annular flange 24 of the bezel-ring into engagement with the annular shoulder 18 of the dial-plate, to 5 thus clamp the supporting-feet 19 of the dial-plate 17 against the annular edge 20 of the center-band 11, thus firmly securing all the parts together, with the movement-unit 13 entirely carried by the dial-plate 17. 10

The invention may be carried out in other specific ways than that herein set forth without departing from the spirit and essential characteristics of the invention, and the present embodiment is, therefore, to be considered in all respects 15 as illustrative and not restrictive, and all changes coming within the meaning and equivalency range of the appended claims are intended to be embraced therein.

I claim:

1. A watch structure comprising: a center-band having a front-edge surface surrounding a front opening; a movement-unit having front and rear movement-plates secured together in spaced relation and adapted to be inserted 25 through said front opening into assembled position; a dial-plate engaging against said front-edge surface of the center-band, said dial-plate being secured to and carrying said movement-unit; and a bezel-ring engaging said dial-plate 30 and said center-band and clamping the dial-plate against said front-edge surface of the center-band. 20

2. A watch structure comprising: a center-band having a front-edge surface surrounding a front opening; a movement-unit having front and rear movement-plates secured together in spaced relation and adapted to be inserted through said front opening into assembled position; a dial-plate engaging against said front-edge surface of the center-band, said dial-plate being secured to and carrying said movement-unit and having an annular shoulder; and a bezel-ring engaging the annular shoulder of said dial-plate and said center-band and clamping the dial-plate against 45 said front-edge surface of the center-band. 35

3. A watch structure comprising: a center-band; a movement-unit having front and rear movement-plates secured together in spaced relation; a dial-plate having feet engaging against 50 said center-band, said dial-plate being secured to and carrying said movement-unit and having an annular shoulder; and a bezel-ring engaging the annular shoulder of said dial-plate and said center-band and clamping the feet of the dial-plate against the center-band. 55

RICHARD H. WHITEHEAD.
